UNITED STATES PATENT OFFICE.

THOMAS NICHOLAS, OF CALUMET, MICHIGAN.

KITCHEN-CABINET.

SPECIFICATION forming part of Letters Patent No. 318,924, dated May 26, 1885.

Application filed January 31, 1885. (No model.)

To all whom it may concern:

Be it known that I, THOMAS NICHOLAS, of Calumet, in the county of Houghton and State of Michigan, have invented a new and 5 Improved Kitchen-Cabinet, of which the following is a full, clear, and exact description.

The object of my invention is to provide a new and improved kitchen-cabinet, especially adapted for holding the implements 10 and the material required for making bread, pie, cake, &c., which cabinet is simple in construction, compact, and handy, and can be closed on all sides and be protected from dust.

The invention consists in the peculiar construction and arrangement of parts, as hereinabove fully described, and pointed out in the 15 claims.

Reference is to be had to the accompanying drawings, forming part of this specification, 20 in which similar letters of reference indicate corresponding parts in all the figures.

Figure 1 is a perspective view of my improved kitchen-cabinet closed. Fig. 2 is an end view of the same closed. Fig. 3 is a front 25 view of the same opened, parts being in section and parts being broken away. Fig. 4 is a cross-sectional view of the same opened. Fig. 5 is a plan view of the same opened.

The oblong frame A, having its end, front, 30 and rear boards placed edgewise, is provided with the legs B.

On the top C a leaf, D, is hinged, which is adapted to close an opening in the top, and to be swung down upon the top.

35 A board, E, is hinged on the front board of the frame, and is adapted to close an opening in the front board, and, when raised, is held in place by a cleat, F, secured on the under side of the leaf D, and adapted to pass in front of the board E.

40 The rear board of the frame is secured, and on the bottom of the recess a dough-board, G, is hinged to swing upward, the free edge of the said board resting upon the front of the top of a flour-box, O. The said dough-board G is provided with the beveled side pieces, J, and with a cross-piece, K, between which and the back piece, L, a box or cavity, M, for tins, patterns, &c., is formed, and at each end of the

same a recess, N, for receiving spice-boxes, is 50 formed, also between the pieces K, L. Below the hinged dough-board the sheet-metal or wooden flour-box O is secured on the frame, and its cover is formed by the hinged dough-board.

On the right-hand side of the dough-board 55 a salt-box, P, is formed, which can be closed by a cover, Q, hinged on the top C.

To the under side of the leaf D a meat-board, R, is secured at the front edge.

At each side of the dough-board a compartment, T, is formed in the top frame for receiving rolling-pins, &c. They are closed by the hinged board E.

By means of the leaf D, the board E, and the cover Q, the cabinet can be closed, so that the 60 dough-boards and the receptacles cannot get dusty or soiled. When the cabinet is closed, it can also be used as a table.

Having thus described my invention, what I claim as new, and desire to secure by Letters 70 Patent, is—

1. In a kitchen-cabinet, the combination, with a frame, of the leaf D, the board E, hinged on the front, the flour-box O, and the hinged dough-board G, forming the cover of the flour-box, substantially as herein shown and described. 75

2. In a kitchen-cabinet, the combination, with the frame A, of the flour-box O, the hinged dough-board G, forming the cover for 80 the flour-box, the salt-box P, and its cover Q, substantially as herein shown and described.

3. In a kitchen-cabinet, the combination, with the frame A, of the flour-box O, the hinged dough-board G, the board E, hinged 85 on the front of the frame, the leaf D, hinged on the top C, and the cleat F, secured on the bottom edge, substantially as herein shown and described.

4. In a kitchen-cabinet, the combination, 90 with the frame A, provided with the compartments T, of the flour-box O, the hinged dough-board G, and the hinged board E on the front, substantially as herein shown and described.

THOMAS NICHOLAS.
